(57) **CLAIM**

We claim the ornamental design for a reverse cube, as shown and described.

DESCRIPTION

FIG. 1 is a bottom perspective view of a reverse cube;
FIG. 2 is a top perspective view thereof;
FIG. 3 is a top plan view thereof;
FIG. 4 is a bottom view thereof; and,
FIG. 5 is a vertical side elevational view thereof, the other
3 side elevational views being the same.

1 Claim, 4 Drawing Sheets

FIG. 1

FIG. 2

FIG. 3

FIG. 4

FIG. 5
